HOSIERY HOLDER

Florence S. De Forte, Buffalo, N. Y.

Application February 28, 1955, Serial No. 34,740

Term of patent 14 years

(Cl. D80—9)

Fig. 2.

Fig. 3.

Fig. 4.

Fig. 1.

Fig. 5.

Fig. 6.

Fig. 1 is a front elevational view of a hosiery holder, showing my new design;

Fig. 2 is a top plan view.

Fig. 3 is an end view taken from the left of Fig. 1;

Fig. 4 is an end view taken from the right of Fig. 1;

Fig. 5 is a bottom plan view; and

Fig. 6 is a rear elevational view thereof.

I claim:

The ornamental design for a hosiery holder, substantially as shown.
